PROPELLER PROPULSION MEANS

John J. Van Eaton, Seathurst, Wash.

Application August 10, 1945; Serial No. 610,155

6 Claims. (Cl. 115—34)

1

The present invention relates to a prime mover, such as a suitable engine or motor, and an operating connection between same and a propeller, such as for example, a propeller used on a boat or the like, it being the object of the invention to improve the stated operating connection through the medium of coaxing driving and driven elements such as can be adjusted and regulated to turn the propeller in the usual forward driving direction, or to turn same in a reverse direction.

In order to achieve results satisfactorily carrying out my aims, I contemplate the adoption and use of novel complementary pulleys, one on the engine drive shaft, and the other on the propeller-equipped driven shaft, said pulleys being rotated in corresponding directions by a belt trained thereover, and being turned in opposed or opposite directions by direct friction-driving contact with each other, the belt being idled at this time.

Another object of the invention has to do with the aforementioned prime mover, propeller-equipped shaft, pulley assembly, and mechanical, manually operated means for supporting and raising and lowering the prime mover whereby to render the pulleys operable to accomplish the aforementioned forward and reverse driving actions.

Other features and advantages will become more readily apparent from the following description and the accompanying illustrative drawings.

In the drawings, wherein like numerals are employed to designate like elemental parts throughout the views:

Figure 1 is an assembled view showing the fragmentary portion of the boat in sections, the remaining parts being in elevation and disclosing the structural assemblage constituting the present invention.

Figure 2 is an end elevation with certain parts of the structure removed to show the construction and assemblage of parts, said view observing Figure 1 in a direction from right to left.

Figure 3 is a perspective view of the engine or prime mover supporting and lifting and lowering unit for hand regulation.

Figure 4 is an enlarged fragmentary sectional view of the driving and driven pulleys.

Figure 5 is a reduced elevational view of the base unit per se, that is, the unit seen in Figure 3 showing how the toggle action performs.

Figure 6 is a view of another type of base unit showing a modified construction, but em-

2

ploying the same lifting and lowering and tilt principle.

Figure 7 is an end elevation, like Figure 2, but showing the stand collapsed, prime mover tilted and drive and driven pulleys frictionally engaged.

Referring now to the general assemblage of parts as seen to best advantage in Figure 1, it will be observed that A designates a fragmentary portion of a suitable boat, this having a bearing B for a shaft C provided with a regular propeller D. A standard E is provided with a bearing F for the propeller shaft C. The letter G designates a suitable engine, motor or equivalent prime mover for powering the propeller. This is situated above a foundation H in the bottom of the boat. These are all old parts as the reference letters denote.

The drive pulley, which is a two-way forward and reverse head, is denoted by the numeral 9, this being on the drive shaft 10. At the outer end it is provided with a V-shaped groove 11 to accommodate a so-called V-belt 12, this being a regular transmission belt. At the inner end it is provided with a friction driving as well as reversing ring 13, this having a marginal V-shaped drive-grip, as brought out to advantage in Figure 4.

The driven pulley 9a, keyed on the propeller or power take-off shaft C embodies a V-shaped grooved portion 11a coaxing with the aforementioned grooved part 11 to accommodate the belt 12. In this instance, the annulus or ring on the pulley 9a is denoted by the numeral 13a, and it is also formed with a marginal V-groove to accommodate the V-grip on the ring or annulus 13. Under ordinary circumstances, the two pulleys 9 and 9a are spaced apart, as shown in Figure 1, and the belt 12 coaxing with its component parts 11 and 11a turns the shaft C to drive the propeller for moving the boat in a forward direction, as is customary. When, however, it is desired to reverse the propeller, the belt 12 is loosened, this by moving the two pulleys 9 and

45. 9a toward each other and bringing the rings 13 and 13a in friction-driving or mating contact, as shown in Figure 4. Here we have a direct friction drive from pulley to pulley, the belt 12 at this time being disengaged and momentarily ineffective.

In order to accomplish the forward and reverse adjustment of the pulleys, it is necessary to provide means for moving same toward and from each other, and also for raising and lowering the prime mover or engine G to accomplish

this. Various types of jacks and lifting and lowering devices might well be employed to achieve this end. I find, however, that the base units which I have herein disclosed are ample and satisfactory. One such unit is shown in Figure 3, the same being generally denoted by the numeral 14. It comprises a base plate 15 rigidly secured on the foundation H. The plate is provided with marginal parallel longitudinal flanges 16 having short upstanding lugs 17 at corresponding ends and vertically elongated arms 18 at opposite ends. The plate 15 is the boat base and the companion plate 19 above is the prime mover base. The latter is suitably constructed and bolted to the bottom of the prime mover and is provided at one end with lugs 20 hingedly connected, as at 21, to the upper ends of the uprights 19. Similar lugs 22 at the opposite ends serve to accommodate the toggle arrangement. This comprises a horizontal rocker shaft 23 mounted for oscillation in bearings in the lugs or ears 17, said rocker shaft being provided with a hand lever 24 at one end. It is also provided with rocker arms 25 which constitute toggle links and which are held adjustably in place by set screws 26 and pivotally connected with companion links 27 hingedly connected to the upper lugs or ears 22. The toggle action is brought out in Figure 5 in which it will be seen that by swinging the lever in the proper direction the base plate 19 is tilted to lower the motor to an elevation to engage the rib 13 with the groove 13a to provide the reversing friction drive between pulleys 9 and 9a. By again righting the motor and plate 19 through the medium of the toggle and lever arrangement, parts 13 and 13a are disengaged and the belt 12 is brought into play to accomplish the regular forward drive for the propeller D.

Another type of adjuster unit for the prime mover is shown in Figure 6, in which it will be seen that the boat base plate is denoted at 28, the motor or prime mover plate at 29, being above the plate 28, and hinged at one end, as at 30, to the uprights 31 on the first plate 28, the latter plate being also provided at its front end with uprights 32 to which the lever 33 pivotally connects. The lever in this instance is provided with a toe or foot 34 which is laterally directed to bear against the free tiltable end of the plate 29. The plate 29 is maintained in normal elevated position by a coiled spring 35 which is interposed between the two plates which surround the bolt 36 anchored on the plate 28, the nut 37 on the bolt serving to adjust the tension of the spring, as is obvious.

In both types of adjusting unit the idea is to have a hand lever for raising and lowering the base plate which is attached to the prime mover so that said prime mover can be raised and lowered to move the pulley arrangement into and out of direct friction-driving contact. The claims are to be interpreted accordingly.

It is understood that in Figure 1 we see the pulleys 9 and 9a arranged so that the belt 12 coacts with the belt receivers 11 and 11a to drive the propeller shaft in the usual forward direction. I have not shown the pulleys together, though it is understood that when the plate 19 is lowered to the position seen in Figure 5, the motor or prime mover G goes down and this permits the rib 13 to engage in the rib-receiving groove 13a, as seen in Figure 4, a fragmentary view which is, evidently, sufficient to illustrate the change from forward to reverse and vice versa.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

I claim:

1. In a structural assemblage of the class described, a boat, a propeller shaft mounted for rotation in relatively fixed bearings on said boat, a propeller keyed on said shaft, a pulley also keyed on said shaft and provided with peripheral individual and selectively usable V-grooved portions, a prime mover including a motion transmitting drive shaft, a second pulley keyed on said drive shaft, said second pulley being provided with a V-groove portion coacting with one of the first-named V-grooved portions, a friction driving belt engageable with the stated 25 V-grooved portions of the respective pulleys, said second-named drive pulley also being provided with a friction driving V-rib, said V-rib coacting with the remaining one of the V-grooved portions of the first-named pulley, said shafts maintaining substantially parallel relationship at all times and said pulleys being bodily shiftable toward and from each other in angular relationship while in a constant plane with each other and while maintaining radial alignment with each other, a normally horizontal elevated plate 30 hingedly mounted at one end on a plane above said propeller shaft, the opposite end of said plate being tiltable toward and from said propeller shaft, said hinged mounting being eccentric to the axis of said first-named pulley, and manually operated mechanical means interposed between the boat and the tiltable end of the plate permitting the plate to be raised and lowered to disengage the two pulleys and to maintain the desired constant plane between the respective pulleys and constant approximate parallelism between the two shafts, said prime mover being mounted on said plate for adjustment in conjunction therewith.

2. In a structural assemblage of the class shown and described, a boat, relatively fixed bearings mounted in said boat, a propeller shaft mounted for rotation in said bearings, a propeller fixed on said shaft, a pulley also fixed on said shaft, a stand comprising a base plate fixedly mounted in a horizontal position in said boat, said base plate having a pair of uprights, a horizontal prime mover supporting plate above the base plate, said prime mover supporting plate being hingedly mounted at one end on the upper ends of said uprights, said hinged mounting being eccentric to the axis of said pulley, manually regulable adjusting means cooperable with the base and prime mover plates for raising and lowering the tiltable end portion of the prime mover plate, a prime mover attached to and movable in conjunction with said prime mover plate, said prime mover having a shaft substantially parallel to the first-named shaft, a pulley on said prime mover shaft, said pulley being disposed in a vertical plane above the first-named pulley and angularly movable toward and from the first-named pulley depending on whether said prime mover plate is in fixed horizontal position or in

tilted position, and a friction driving belt trained over said pulleys.

3. In a structural assemblage of the class described, a boat, a substantially horizontal shaft mounted for rotation in bearings provided in said boat, a driven pulley keyed on said shaft, a vertically disposed prime mover including a substantially horizontal drive shaft substantially parallel to said first shaft, a drive pulley keyed on said drive shaft, said pulleys being normally spaced apart and in alignment with each other, the periphery of the driven pulley having V-grooves, the periphery of the drive pulley having a V-groove and a V-rib adapted to seat in one of the V-grooves in the driven pulley, a drive belt trained over coacting grooves in the respective pulleys, and lifting and lowering means interposed between the boat and bottom of the prime mover and including a tiltable plate tiltable and swingable in a vertical plane toward and from the boat and at right angles to the respective shafts, whereby to keep the two pulleys in constant alignment with each other and to maintain the shafts in substantially constant parallelism at all times, in conjunction with a second plate secured to the boat and including fixed uprights, said first-named plate being mounted on said uprights, and means coacting with corresponding ends of the respective plates for moving the first plate toward and from the second plate.

4. In a structural assemblage of the class described, a boat, a substantially horizontal shaft mounted for rotation in bearings provided in said boat, a driven pulley keyed on said shaft, a vertically disposed prime mover including a substantially horizontal drive shaft substantially parallel to said first shaft, a drive pulley keyed on said drive shaft, said pulleys being normally spaced apart and in alignment with each other, the periphery of the driven pulley having V-grooves, the periphery of the drive pulley having a V-groove and a V-rib adapted to seat in one of the V-grooves in the driven pulley, a drive belt trained over coacting grooves in the respective pulleys, and lifting and lowering means interposed between the boat and bottom of the prime mover and including a tiltable plate tiltable and swingable in a vertical plane toward and from the boat and at right angles to the respective shafts, whereby to keep the two pulleys in constant alignment with each other and to maintain the shafts in substantially constant parallelism at all times, in conjunction with a second plate secured to the boat and including fixed uprights, said first-named plate being mounted on said uprights, and means coacting with corresponding ends of the respective plates for moving the first plate toward and from the second plate including lever controlled toggle means.

5. As a component unit of a structural assemblage of the class shown and described, a prime mover raising and lowering stand comprising a base plate adapted to be fixedly mounted in a horizontal position in a boat, said base plate being provided at one end with a pair of uprights, said base plate being substantially rectangular in plan view, a complementary horizontal prime mover supporting plate rectangular and disposed in superposed parallelism above said base plate and hingedly connected at one end to the upper ends of said uprights, a rocker shaft mounted on said base plate, a lever connected to for operating said shaft, rocker arms secured on said rocker shaft and constituting toggle-links, additional toggle-links pivotally mounted on the free tiltable end of said prime mover plate and pivotally connected with the first named toggle-links.

20 6. A prime mover supporting and tilting stand comprising a base plate adapted to be mounted in a horizontal position in a boat, said base plate being provided with a pair of uprights, a complementary plate hingedly mounted at one end on the upper ends of said uprights and adapted to support a prime mover, a bolt attached to and rising vertically from said base plate and extending through a complementary aperture in said prime mover supporting plate, a coiled spring surrounding said bolt and interposed between the respective plates and adapted to support the prime mover plate in a normally horizontal plane parallel to said base plate, upright means also mounted on and rising from said base plate, a hand operated lever pivoted on said upright means and being provided with a lateral foot releasably engageable with the tiltable end portion of said prime mover plate for pressing the latter down to an angular position against the tension of the spring.
